Attorney

UNITED STATES PATENT OFFICE.

FRANK W. BLAKE, OF BROOKLYN, NEW YORK, ASSIGNOR TO UNDERWOOD COMPUTING MACHINE COMPANY, OF NEW YORK, N. Y., A CORPORATION OF NEW YORK.

COMPUTING MACHINE.

Application filed May 26, 1920. Serial No. 384,312.

To all whom it may concern:

Be it known that I, FRANK W. BLAKE, a citizen of the United States, residing in Brooklyn Borough, in the county of Kings, 5 city and State of New York, have invented certain new and useful Improvements in Computing Machines, of which the following is a specification.

This invention relates to the registers of 10 computing machines, especially those of the type known as the Underwood standard bookkeeping machine, which both type-writes and computes.

In the Underwood machine, the registers 15 which display the totals, and which are located at the extreme front of the machine, are usually in the shadow of the operator, so that they are not easily read.

According to the present invention, the 20 registers are provided with electric lights to illuminate them, and provision is made whereby when any register is out of use, its light is automatically extinguished, thereby economizing electricity. Other advantages are gained, inasmuch as a check is 25 also afforded for the benefit of the operative, who is apprised by the extinguishing of any light that the dials in that register have all been returned to zero. The operative is also 30 able to distinguish easily which registers are in active use, and it is never necessary to scrutinize the dials to ascertain whether they all stand at zero. In other words, in a machine having several registers, there may 35 be a separate light for each register, and each light may be separately controlled by its own register, so that the state of any register may be recognized without attempting to read the dials.

40 The register lights may be connected to an ordinary lighting circuit, and may be provided with a suitable resistance. In some cases, the resistance may be in the form of an electric desk lamp, which customarily 45 is placed in position to illuminate the keyboard. A telltale or warning signal is afforded, in case any lamp burns out. Preferably, the register lights may be connected in series with the desk lamp, and may be 50 short-circuited when the dials of the register stand at zero, each register light being separately short-circuited by the movement of its own register bar or bail.

The closing and opening of the register

lamp circuit or circuits may be dependent 55 upon the movements of a bar or bail, which is usually provided at each register to control a type which prints a clearance star upon the work-sheet.

Other features and advantages will here- 60 inafter appear.

In the accompanying drawings,

Figure 1 is a fragmentary plan view of the front of an Underwood standard book-keeping machine, the cover and many other 65 parts being largely broken away.

Figure 2 is a diagrammatic, sectional, side view of the same.

Figure 3 is a fragmentary perspective view of a register and a diagram of its electric connections when used with another 70 register, as embodied in one form of the invention.

Figure 4 is a diagram of wiring, showing an alternative form of the invention. 75

Figure 5 is a side view of the register and electric contact seen in Figure 3.

Figure 6 is a side view, somewhat similar to Figure 5, but showing the contact for the form of the invention illustrated in Fig- 80 ure 4.

In the Underwood standard bookkeeping machine, register or computing wheels 10 are rotated by rack bars 11 on the front ends of pin bars 12, which latter are adapted to 85 be driven forward at the actuation of a general operator 13, herein diagrammatically shown as adapted to be driven forward by drawing forward the handle 14 used on some types of the Underwood standard bookkeep- 90 ing machine.

The rack bars 11 are driven varying distances according to the pins set up on the pin bars 12, the pins being set in the usual manner shown in the patent to Hans Hanson, 95 No. 1,278,812, dated September 10, 1918. One form of said machine, having several registers is shown in the patent to Frederick A. Hart, No. 1,281,953, dated October 15, 1918.

In order to enable a sign to be printed when all the wheels stand at zero for proving the accuracy of copying the amount of the total, or for proving that the machine is clear when work is begun, there is usually 105 provided a star-printing key 15 which effects printing by releasing a star type-bar (not shown herein, but one form of which is

shown in the patent to Hoyt, No. 1,256,309). The star type-bar is under the control of a rock arm 16, upon which the lower end 17 of the star-key 15 rests. Unless all the 5 wheels 10 in its register stand at zero, the star-key 15 is locked by a lug 18 near the upper end of its stem, because a locking bail 19 is held in the path of said lug whenever any wheel of its register shows any digit 10 other than zero. To bring about this result, each wheel 10 usually comprises teeth 20, which are engaged by a detent 21, adapted to normally seat itself to a limited extent between any two of the teeth 20. When, 15 however, any wheel 10 of a register stands at zero, its detent 21 can seat itself more deeply, because it seats in the cut-out portions 22 of the teeth 20 which then stand adjacent its detent 21.

20 The bail 19 of any register extends past all the detents 21 of that register, and is adapted to engage tails 23 on said detents, with the result that its spring 24 swings the bail 19 rearwardly, carrying its detents into 25 the teeth 20 of its register wheels 10, and thus, whenever said wheels stand at zero, carrying the detents 21 into the cut-out portions 22. The bail 19 is fast to rock arms 25, so that it swings as a whole to and from 30 its wheels 10, with the result that when any detent 21 engages with any teeth 20, which are not cut away, the bail 19 is swung outwardly to its Figure 5 position, thus blocking its star-printing key 15 by underlying 35 the lug 18 thereof.

Each wheel 10 usually has nine digits, besides the digit "0", usually running from "1" to "9", and so positioned that they may be read through the sight-opening 26 in the 40 top 27 of the casing which contains the computing mechanism. The sight-opening 26 is usually covered with a piece of glass 28 of considerable thickness to avoid any likelihood of its breaking. Thus, digits 45 on the wheels 10 have to be read through the glass 28, and, for structural purposes, the wheels 10, while close to the top 27, are necessarily clear thereof, with the result that only a small amount of light reaches the 50 numerals or digits on the wheels 10. The amount of light is necessarily considerably restricted, because there is provided a shield 29 adjacent the front and rear margins of the sight-opening 26, to obscure the numerals or digits adjacent those to be read, thus 55 preventing the typist from erroneously copying a digit from the wrong row.

The shields 29 are usually painted strips upon part of the glass 28. The light upon 60 the digits on the wheels 10 is also poor, owing to the fact that the light coming from the rear of the machine is cut off by the front of the frame of the machine, and the rising rear portion 30 of the top 27 also cuts 65 off some light.

In order to illuminate the wheels 10, there is provided, according to the present disclosure, a narrow electric light 31, which may be of the form used in telephone switchboards and a little larger than a lead pencil, 70 said light being held over and adjacent the center of its register by small brackets or fingers 32 held by screws 33 to the portion 30 of the top 27. The light or lamp 31 may lie axially of the register, behind but adjacent 75 the shield 29, so that its direct rays can hardly be visible through the glass 28, and yet the light 31 is near enough the line of readable numerals on the wheels 10 to effectively illuminate them. By utilizing a 80 lamp of the character described, it has become possible to illuminate the wheels 10 in the exceedingly narrow space between them and the top 27 of the computing casing.

Since the lamps 31, of which there is one 85 for each register, advantageously use only a small voltage, each lamp is advantageously connected in series with a suitable resistance, which is herein shown as a bracket-mounted, keyboard-illuminating lamp 34, 90 which usually is carried upon a standard to overhang the keyboard of the machine to illuminate it. Such lamps are usually either 25 or 40 watt tungsten lamps, and, therefore, when connected in series with a lamp 31 of 95 the type described, the additional resistance does not perceptibly vary the brilliancy of the lamp 34. Where the machine has two or more registers, connections may be provided such that each lamp 31 may be in 100 series with the resistance or bracket lamp 34, and yet in nowise interfere with the continuous burning of the lamp 34.

Where there are several registers, as illustrated at 35 and 36, at the left and right, 105 respectively, in Figure 1, and also in Figure 3, there may be a lamp 31 for one register, and a similar lamp 37 for the other register, each lamp adapted to be maintained lighted or dark by the star-locking bail of its own 110 register. To accomplish these results, the circuit for illuminating the lamp, 31 of the register 35, may include a conductor 38 running from the lamp 34, and forming part of its circuit, said conductor 38 being connected to a conductor 39 in series with the lamp 31, and thence connected by a conductor 40 to the main 41 in series, as will presently appear. Under such conditions, the lamp 34 is in series with the lamp 31 between its 120 conductor 43 connected to one main 42 and its conductor 38 connected to the other main 41.

This is the condition which exists whenever the bail 19 is held outward to lock its 125 star-printing key 15. Whenever, however, all the wheels 10 stand at zero, the spring 24 swings the bail 19 rearwardly, that is to say, to the right at Figures 2 and 3, thus allowing an electric terminal 44, which has 130

been held clear of a terminal 45, as shown in Figures 1 and 5, to now contact with the terminal 45, thus closing a short-circuit including two conductors 46 and 47 respectively connected to the main 41 and to the conductor 38, to short-circuit the lamp 31, as shown in Figure 2 and in Figure 3 at the left. This extinguishes the lamp 31 and thereby indicates that the wheels 10 of its 5 register stand at zero, and also indicates that the star-printing key 15 has been released or unlocked, so that it may be operated for proving that the total has been accurately copied and that the register is clear. In this 10 connection it is to be noted that the register lamp, such as 31, serves the double purpose of giving two different kinds of indications. When the register lamp is lit, it thereby indicates that the register contains a number; 15 and when the register lamp is extinguished, it thereby indicates that the clearance-proving key, such as 15, may be operated. In the particular embodiment of the invention illustrated in the drawings, the universal member or bail 19, besides controlling the register lamp 31, also controls the corresponding star-key 15. Similar star-keys 15 are provided for each of the registers of the machine, as shown in Figure 1 for the 20 registers 35 and 36. The terminal 45 may be a stiff plate fast to, but electrically insulated from, the usual front cross-bar 48 of the frame which carries the computing mechanism. The spring-terminal 44 may be a resilient plate electrically insulated both from 25 the cross-bar 48 and from the bar forming the terminal 45, there being, for this purpose, interposed behind a plate 49, of which the terminal 44 is the end, an insulating sheet 50, the upper end of which insulates the bail 19 from the plate 49. The two terminals 44 and 45 may be held to the bar 48 by a screw 51, suitably insulated from them by washers or other devices, and the 30 wires 46 and 47 may be respectively connected to the two terminals 44 and 45 at their bottoms, as shown in Figures 2 and 5. To enable the lamp 37, of the register 36, to be lighted, it is interposed between the 35 conductor 38 and the conductor 39, thus normally being in series with the lamps 34 and 31. In order to extinguish the lamp 37, it may be short-circuited, as in Figure 3, by a conductor 52 which is electrically connected to the conductor 47, and ends in a terminal or contact 53, against which a terminal or contact 54 is adapted to lie, so that the two contacts form a circuit with the conductors 52 and 55, the latter extending 40 from the terminals 54 to the conductor 38, short-circuiting the lamp 37. Excepting at their upper ends, which are adapted to be separated, the contact plates or terminals 53 and 54 are insulated from each other by an 45 interposed insulating strip 50, and also are insulated from the frame bar 48, and are secured thereto by means of a screw 51 similarly to the contact-forming plates or terminals 45 and 49. The terminal 54 is adapted to be swung out to break the short-circuit 50 52, 55, and thereby cause the lamp 37 to be lit, to show that the register 36 is not at zero, and, for this purpose, the register 36, shown at the right in Figures 1 and 3, is provided with a bail 56, which may be identical with the bail 19, being controlled by detents 57 which are controlled by the wheels 10 of the register 36, precisely as are the detents 21 of the register 35. The connections, therefore, are such that the bail 56 is 55 adapted to allow the terminals 53 and 54 to remain in contact when the wheels of the register 36 all show zero, as in Figure 1 at the right, but, at other times, and as shown in Figure 3 at the right, the bail 56 holds 60 the terminal 54 clear of the terminal 53, with the result that the short-circuit 52, 55, is broken and the lamp 37 is lighted. The mains 42 and 41 may be provided with the usual switch 58, which is adapted to extinguish all the lights 34, 31 and 37. When both of the short circuits, around the register lamps 31 and 37, are in closed condition, the desk lamp 34 will provide sufficient resistance to prevent a destructive rush of 65 current through the closed circuit thus provided. Should one of the register lamps 31 or 37 fail, the operator will be apprised of this fact through the extinguishing of the desk lamp 34. 70

In Figures 4 and 6 is shown a somewhat modified construction. In Figure 4, the current, instead of passing through the lamp 34, passes through a resistance 59, which serves the purpose of the lamp 34 in protecting the lamps 31 and 37 of Figure 4 from excessive current and may itself be a tungsten lamp. The lamps 31 and 37 of Figure 4, however, are shown in parallel, and may be operated from mains 60 and 61, across 75 which they are connected in parallel, there being provided for the lamp 31 a spring-terminal 62, which normally tends to spring clear of the terminal 63, as shown in Figures 4 and 6, and there being provided for the lamp 37 a spring-terminal 64, which normally tends to spring clear of a fixed terminal 65. Each of the terminals 62 and 64, however, is of the form shown in Figure 6, in which the bail 19 or 56, as the case 80 may be, is adapted to press the terminal 62 against the terminal 63 whenever it is swung out, because the wheels of its register are reading some other number than zero. The system of connections shown in Figure 4, in 85 most respects, is fully as efficient as the system of connections shown in Figure 3, the main objection being that, if either of the lamps 31 or 37 burns out, the typist may be deceived by the fact that the burnt-out 90

lamp does not light. In each form of the invention, however, the lamp of either register is adapted to show whether its register stands at zero, and, whenever its 5 register does not stand at zero, the digits on the wheels thereof are adequately lighted, thus being of especial utility in rapid operation of the machine, and also furnishing light to relieve the eyes of the typist at the 10 time the eyes need to be used on the hitherto poorly-illuminated register wheels. In the Underwood standard bookkeeping machine, referred to above, and to which the present invention is shown applied, the surfaces of 15 the register wheels are usually black with white numerals, instead of being brass with black numerals, as is the case in many types of computing machines. The white numerals of the Underwood standard book- 20 keeping machine are especially well adapted for use in connection with the present invention.

Variations may be resorted to within the scope of the invention, and portions of the 25 improvements may be used without others.

Having thus described my invention, I claim:

1. In a combined typewriting and computing machine, the combination with a casing and a register comprising dial-wheels lying close to the casing, of a lamp within 30 said casing and lying along said wheels, a screen adapted to keep the direct rays of the lamp from striking the opening in the 35 casing through which the wheels may be read, a device controlled by the wheels to occupy one position with the register in one predetermined relative arrangement, and another position with the register-wheels in 40 another predetermined relative arrangement, and connections for controlling said lamp by said device.

2. In a computing machine, the combination with a casing and a register comprising 45 dial-wheels, of a lamp for illuminating the wheels, a device controlled by the dial-wheels to occupy one position with the register in one condition, and another position with the register in another condition, and connec- 50 tions whereby the device controls the lamp.

3. In a computing machine, the combination with a casing and a register comprising dial-wheels, of a lamp for illuminating the 55 wheels, and means for lighting said lamp when any one of the wheels is moved from its zero position.

4. In a computing machine, the combination with a casing and a register comprising dial-wheels, of a lamp, a pair of mains carrying 60 a current for said lamp, a register-lamp connected in series with the first lamp, and means for short-circuiting said register-lamp by movement of the register-wheels to zero.

5. In a computing machine, the combination 65 with a casing and a register comprising

dial-wheels, of a lamp, mains carrying a current for said lamp, a register-lamp in series with the first lamp, terminals normally tending to short-circuit the register-lamp, and means controlled by the register-wheels for 70 making said terminals ineffective whenever any wheel moves away from zero.

6. In a computing machine, the combination with a casing and a plurality of registers comprising dial-wheels, of a lamp, 75 mains for supplying current to said lamp, a register-lamp for each register in series with the first-named lamp, a separate connection for each register-lamp adapted to short-circuit it, and means operated by the 80 turning of any wheel in a register for making the short-circuit for that register ineffective when any wheel thereof turns from zero.

7. In a computing machine, the combination with a casing and a plurality of registers comprising dial-wheels, of a register-lamp for each register, mains for supplying current to said lamps, and a connection operated by each register for lighting its lamp 90 from the mains when any wheel thereof moves away from zero.

8. In a computing machine, the combination with a casing and a register comprising dial-wheels, of a detent for each wheel, a 95 bail universal to said detents, a spring normally tending to move said bail, the connections being such that any wheel not standing at zero moves its detent to move the bail against its spring, and a register-lamp controlled by said bail.

9. In a computing machine, the combination with a casing and a register comprising dial-wheels, of a detent for each wheel, a bail 105 universal to said detents, a spring normally tending to move said bail, the connections being such that any wheel not standing at zero moves its detent to hold the bail against its spring, a register-lamp, a circuit for said register-lamp comprising terminals adjacent said bail and controlled thereby, and a spring holding one of the terminals against the bail, the connections being such that the bail is held against its spring by any wheel not standing at zero. 110

10. In a computing machine, the combination with a casing and a plurality of registers comprising dial-wheels, of a lamp for each register, mains carrying a current 115 for said lamps, a separate bail for each register adapted to occupy one position when all its wheels stand at zero and to occupy another position when any wheel stands away from zero, and a terminal for each lamp controlled by the bail of its register.

11. In a computing machine, the combination with a casing and a plurality of registers comprising dial-wheels, of a lamp for each register, mains carrying a current for 120

- said lamps, a separate bail for each register adapted to occupy one position when all its wheels stand at zero and to occupy another position when any wheel stands away from 5 zero, a terminal for each lamp controlled by the bail of its register, a general illuminating lamp in series with said register-lamps, and short-circuits for the register-lamps through which the terminals are effective.
- 10 12. In a computing machine, the combination with a casing and a plurality of registers comprising dial-wheels, of a lamp for each register for illuminating its wheels and lying within the casing, a terminal for each 15 lamp adjacent its register to enable the register to control the lamp circuit, and a device universal to the wheels of each register adapted to control the terminal for that register, to cause its lamp to be lighted whenever 20 any one of its register-wheels moves away from zero.
13. In a computing machine, the combination with a casing and a plurality of registers comprising dial-wheels, of a main lamp, 25 a register lamp for each register, mains for carrying a current for said main lamp, said register-lamps in series with the main lamp, short circuits for the register-lamps, and circuit-controlling devices operated by each 30 register to control the short circuit of its lamp.
14. In a computing machine, the combination with a key for printing a clearance sign, of a register, a bail for said register controlling said key to render it operable only 35 when the register is clear, a lamp for said register to indicate the condition of said key as to operability, and a circuit for said lamp controlled by said bail to enable the lamp to 40 indicate when said key may be operated.
15. In a computing machine, the combination with a key for printing a clearance sign, of a register, means controlled by said register for controlling said key to render it operable only when the register is clear, a lamp for said register to indicate the condition of said key as to operability, and a circuit for said lamp controlled by said means to enable the lamp to indicate when said key 45 may be operated.
16. In a computing machine, the combination with a plurality of registers, of a key for each register for printing a clearance sign, a separate bail for each register for controlling the key thereof to render it operable only when the register is clear, and a separate lamp for each register automatically controlled by its bail to enable the lamp to indicate when said key may be operated.
- 50 17. In a computing machine, the combination with a plurality of registers, of a key for each register for printing a clearance sign, a separate set of detents for each register for controlling its key to render it operable only when the register is clear, and a 55 separate lamp for each register automatically controlled by its detents to enable the lamp to indicate when said key may be operated.
18. In a computing machine, the combination with a plurality of registers, of a key for each register for printing a clearance sign, a separate bail for each register for controlling the key thereof to render it operable only when the register is clear, a 60 separate lamp for each register automatically controlled by its bail to enable the lamp to indicate when said key may be operated, and a telltale lamp for the computing machine adapted to be extinguished whenever a register-lamp which should be lit is extinguished.
19. In a computing machine, the combination with a register comprising number-wheels, of a key for printing a clearance sign, key-controlling means operated by the register for controlling said key to render it operable only when the register is clear, and indicating means automatically controlled by said key-controlling means for 65 indicating when said key may be operated to enable the printing of the clearance sign.
20. In a computing machine, the combination with a register comprising numeral-bearing elements for indicating the results of computing operations, of a key for printing a clearance sign, means controlled by the register for controlling said key to render it operable only when the register is clear, and means other than said numeral-bearing 70 elements automatically controlled by the register for indicating whether said key may be operated to enable the printing of the clearance sign.
21. In a computing machine, the combination with a register comprising number-wheels, of a lamp for the register, a key for printing a clearance sign when the number-wheels stand at zero, and means controlled by the register for concomitantly locking 75 said key and lighting the lamp to indicate that said key is locked when any number-wheel moves away from its zero position, and for concomitantly releasing said key and extinguishing the lamp to indicate that said key 80 may be operated for printing the clearance sign when the number-wheels are returned to the zero position.
22. In a computing machine, the combination with a register comprising number-wheels for indicating the results of computing operations, an electric lamp for illuminating the numeral-bearing faces of the number-wheels, an electric circuit in which the lamp may be included to light the lamp, 85 a key for printing a clearance sign, means including a circuit controller in control of the electric circuit, and a member universal to and operable by the number-wheels for concomitantly locking said key and operat-

- ing the circuit controller to light the lamp to indicate that said key is locked when any one of the number-wheels is moved away from its zero position, and for concomitantly 5 unlocking said key and extinguishing the lamp to indicate that said key may be operated when all of the number-wheels are returned to the zero position.
23. In a computing machine, the combination with a register comprising number-wheels for indicating the results of computing operations, of automatically-operated illuminating means to indicate that a number has been run up on the number-wheels.
- 10 24. In a computing machine, the combination with a register comprising number-wheels for indicating the results of computing operations, of a lamp for the register, and means controlled by the register for 15 lighting the lamp when any number-wheel moves away from its zero position.
25. In a computing machine, the combination with a register comprising number-wheels for indicating the results of computing operations, of a lamp for illuminating the numeral-bearing faces of the number-wheels, and means controlled by the register for lighting the lamp when any number-wheel moves away from its zero position.
- 20 26. In a computing machine, the combination with a plurality of registers, each including number-wheels, of an electric register-lamp for each register, and means controlled by each register for establishing a 25 lighting circuit through its lamp when any number-wheel of the register moves away from zero.
27. In a computing machine, the combination with a plurality of registers, each 30 including number-wheels, of an electric register-lamp for each register, a universal member for each register operable by the number-wheels to occupy one position when all the number-wheels stand at zero, and to 35 occupy another position when any number-wheel stands away from zero, and means operable by each universal member for establishing a lighting circuit through the corresponding register-lamp when any number-wheel of the register moves away from zero.
- 40 28. In a computing machine, the combination with a plurality of registers, each including number-wheels, of an electric register-lamp for each register for illuminating the numeral-bearing faces of its number-wheels, a lamp circuit for each register-lamp, means including a circuit-controller for each register in control of its lamp circuit, and a member universal to and operable 45 by the number-wheels of each register for operating the circuit controller for that register to cause its lamp to be lighted whenever any one of its number-wheels moves away from zero.
- 50 29. In a computing machine, the combination with a plurality of registers, each including number-wheels, of an electric register-lamp for each register, a lighting circuit in which the register-lamps may be included in series, and means including a circuit-controller for each register operated by the turning of any number-wheel of a register away from zero for including the register-lamp of that register in the lighting circuit to light the lamp.
- 55 30. In a computing machine, the combination with a plurality of registers, each including number-wheels, of an electric register-lamp for each register, a lighting circuit in which the register-lamps may be included in series, a normally closed short circuit for each register-lamp, and means operated by the turning of any number-wheel in a register away from zero for opening the short circuit of the register-lamp for that register to light the register-lamp.
- 60 31. In a computing machine, the combination with a plurality of registers, each including number-wheels, of an electric register-lamp for each register, a main electric lamp, a lighting circuit including the main lamp and in which the register-lamps may be included in series, and means including a circuit-controller for each register operated by the number-wheels for including the register-lamp for that register in the lighting circuit to light the register-lamp when any number-wheel of a register is turned away from zero.
- 65 32. In a computing machine, the combination with a plurality of registers including number-wheels, of a main resistance, an electric register-lamp for each register, a lighting circuit including the main resistance and in which the register-lamps may be included in series, a normally closed short circuit for each register-lamp, and means operated by the number-wheels for opening the short circuit to light the register-lamp when any number-wheel of a register is turned away from zero.
- 70 33. In a computing machine, the combination with a plurality of registers, each including number-wheels, of a main electric lamp, an electric register-lamp for each register for illuminating the numeral-bearing faces of the number-wheels thereof, a lighting circuit including the main lamp and in which the register-lamps may be included in series, and a member universal to and operable by the number-wheels of each register for including the register-lamp for that register in series in the lighting circuit with the main lamp to light the register-lamp when any number-wheel of a register is turned away from zero.
- 75 34. In a computing machine, the combination with a plurality of registers, each including number-wheels, of a main resistance, an electric register-lamp for each register, a lighting circuit including the main resistance and in which the register-lamps may be included in series, and a member universal to and operable by the number-wheels of each register for including the register-lamp for that register in series in the lighting circuit with the main lamp to light the register-lamp when any number-wheel of a register is turned away from zero.

register for illuminating the numeral-bearing faces of the number-wheels, a lighting circuit including the main resistance and in which the register-lamps may be included in series, a normally closed short circuit for each register-lamp, a circuit-controller in control of each short circuit, and a member universal to and operable by the number-wheels of each register for operating the circuit-controller to open the short circuit to light the register-lamp whenever any one of the number-wheels is moved away from zero.

35. In a computing machine, the combination with a plurality of registers, each including number-wheels, of a detent for each number-wheel, a member universal to the detents for each register to be operated thereby, a spring normally tending to move the universal member into operative relation with the detents, each number-wheel being adapted when moved away from zero to move its detent and thereby to move and hold the universal member against the tension of its spring, an electric register-lamp for each register, a lighting circuit in which the register-lamps may be included, and means in control of each register-lamp including contact-terminals controlled by the

universal member to light the register-lamp whenever a number-wheel is moved away from zero.

36. In a computing machine, the combination with a plurality of registers, each including number-wheels, of a detent for each number-wheel, a member universal to the detents for each register to be operated thereby, a spring normally tending to move the universal member into operative relation with the detents, each number-wheel being adapted when moved away from zero to move its detent and thereby to move and hold the universal member against the tension of its spring, a main resistance, an electric register-lamp for each register connected in series with each other and with the main resistance, a normally closed short circuit connected in multiple with each register-lamp, and a circuit-controller in control of each short circuit and operable by the universal member to open the short circuit whenever a number-wheel moves away from zero.

FRANK W. BLAKE.
